UNITED STATES PATENT OFFICE.

WINFRED T. POWELL, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,303,958.

Specification of Letters Patent. Patented May 20, 1919.

Application filed July 19, 1915. Serial No. 40,704.

To all whom it may concern:

Be it known that I, WINFRED T. POWELL, a citizen of the United States of America, and resident of Chicago, county of Cook, and 5 State of Illinois, have invented certain new and useful Improvements in Automatic Telephone Systems, of which the following is a specification.

My invention relates to automatic telephone systems, and more particularly to 10 those systems which comprise a plurality of exchanges between which connection may be established automatically by the individual subscribers. A common method of fixing 15 the amount to be charged for service in these systems is to provide each subscriber's line with a registering device or meter which will register once for each successful originating call. The subscriber's meter may be 20 so arranged that it will not register on calls to a certain class of subscribers such as officials of the telephone company, etc., but ordinarily it cannot discriminate between any 25 of the calls that are to be charged, *i. e.*, it either registers or it does not register.

Now in systems where the exchanges are 30 widely distributed it is often desirable to make a small toll charge between certain exchanges, the amount usually depending on 35 the distance between the points connected. For example, consider three automatic exchanges A, B and C. Subscribers at A may call other subscribers in the same office for the minimum amount, which may be five 40 cents. For connection between A and B, if B is located at some distance from A, it may be desirable or necessary to charge an amount in excess of the minimum; likewise for connections between A and C it may be desirable 45 to charge a still greater amount.

Heretofore it has been the practice to restrict the automatic calling to those exchanges which lie within a comparatively local area. If the systems contain outlying 50 exchanges or offices, the subscribers are not allowed to connect with such exchanges automatically but are required to call a checking operator and notify her of the connection desired. The operator is provided with suitable means for extending the connection 55 to the desired party and is expected to record the name and number of the calling party together with the amount to be collected for the call.

Efforts have been made in the past to devise means for automatically collecting the charges to exchanges having different rates but so far as known these efforts have not been entirely successful.

The object of my invention is the provision of a new and more practicable method of automatically charging for calls having different rates. In my improved system the digit of the called number which determines to which exchange the connection is to be 60 extended also determines the amount of toll to be charged. I employ no apparatus at the subscriber's station other than the regular automatic telephone but preferably use so called meters individual to the subscribers' lines and located at the exchange. I 65 provide simple and efficient means at each exchange for actuating the meter of a calling subscriber a variable number of times depending on the exchange to which connection was extended. For example if connection is made with a subscriber in the same or nearby office, the meter will be actuated once. If, however, a call is made to a point 70 which carries an additional charge of ten cents the meter will be actuated three times. It is apparent that in this manner various amounts may be registered by suitable actuations of the subscriber's meter. I desire 75 to explain that while the metering in my system is entirely automatic when once started it will not begin to register until started by an operator in the distant exchange. I provide means by which a supervising operator may listen in on the incoming 80 trunks at the proper time, as indicated by a lamp signal, to ascertain whether or not the answering party is the one wanted. If the call is successful the operator will press for an instant a button associated with the 85 signal lamp. This starts the mechanism in the originating office which proceeds to actuate the meter the required number of times as determined by the first digit of the called 90 number.

Having briefly described the object and scope of my invention I will now proceed to a more detailed description of the same, reference being had to the accompanying drawings.

In the drawings, Figures 1, 2 and 3 show a complete connection between a calling substation A and a called substation A' located

in separate exchanges in an automatic system embodying the principles of my invention. That portion of the apparatus which is peculiar to my invention is shown in Fig. 2, the remaining parts being well known in the art, and included only in order to more clearly show the operation of my improvement.

At A there is represented an automatic 10 substation to the line conductors of which there is allotted at the central office an individual or line switch C. At D there is shown a master switch for controlling a group of the switches C. The line switches 15 of this group have common access to a number of trunk lines which lead to first selector switches E. A number of first selectors have common access to a group of repeaters R. Each repeater is connected to a trunk line 20 L L' extending to a distant exchange where the line terminates in a second selector F. A number of second selectors have common access to a group of connectors H by means of which connection may be completed with 25 subscribers' lines. At S is shown a rotary switch associated with the repeater R. At P are shown the essentials of a supervising operator's position in the distant exchange. At B is shown a battery having one terminal 30 grounded and at B', a second battery also having one terminal grounded. Associated with each subscriber's line is a meter M.

The substation shown herein may be of 35 any suitable or approved type and comprises the usual receiver 2, transmitter 3, ringer 4 and condenser 5. Being an automatic substation it is also provided with an impulse transmitter or calling device, which 40 is represented herein by a pair of impulse springs 6 and 7 and an impulse wheel 8, which latter is assumed to be controlled through the medium of a finger hole dial (not shown) in such a manner that the impulse springs 6 and 7 may be momentarily 45 separated a number of times corresponding to each digit of the called number.

The line switch C, which is associated with the line of substation A, is of the general 50 type of line switch shown in British patent to R. W. James No. 26,301 of 1906, which is well known in the art. This line switch comprises among other details a plunger (not shown) attached to the end of 55 a so called plunger arm 14 which is controlled by the magnet 13. The magnet 13 comprises two windings, the pull-in winding 18 and the holding or cut-off winding 17. The winding 18 operates both the 60 plunger arm 14 and the cut-off armature 15, while the winding 17 is only strong enough to operate the armature 15 and to hold the plunger arm 14 in an operated position after it has once been operated by the pull-in 65 winding 18. The circuit of the pull-in

winding is controlled by the line relay 12, which is slow acting, *i. e.*, it retains its armature for an instant after the energizing circuit is broken. When the plunger arm 14 is operated, the plunger is forced into a 70 bank of springs, forcing the springs 27, 28, 29, 30 into engagement with the contacts 31, 32, 33, 34, respectively. Although only one set of springs and contacts (27-34) is shown, it is to be understood that each line 75 switch is provided with a plurality of such sets, each set forming the terminal of a trunk line leading to a selector switch E. Each trunk line is connected in multiple to the corresponding springs of all the switches 80 of the group which is controlled by the master switch D.

The master switch D is of the same general type as that disclosed in British patent to R. W. James No. 26,301 of 1906, above 85 referred to, being, however, more nearly of the particular type disclosed in British patent to T. G. Martin No. 1419 of 1910. The function of the master switch, as is well known, is to maintain the plungers of all 90 the idle line switches in position before an idle trunk line.

The selector E is of the general type of selector disclosed in U. S. Letters Patent No. 815,321 granted March 13, 1906, to 95 Keith, Erickson and Erickson, the circuits being modified in order to operate in a system in which the impulses are delivered over both sides of the line in series. Among other details, the selector E comprises a set of 100 wipers 78, 79 and 80 carried upon a vertically and rotatably movable shaft (not shown). The shaft is actuated in its vertical movement by the magnet 46 and in its rotary movement by the magnet 47. The 105 selector is controlled by means of the line relay 40. Means for permitting the switch shaft to be restored to normal position are provided in the release magnet 42, which, upon energizing, withdraws the retaining 110 pawls from the shaft. The springs 75 are permitted to close only when the switch shaft has been raised one or more steps from its lowest position. The relays 41 and 43 are slow acting, *i. e.*, they will retain their 115 armatures for an instant after the energizing circuit is broken.

The repeater R has no moving parts but consists simply of relays mounted in any suitable manner. Relays 102 and 101 are 120 slow acting, *i. e.*, their armatures are retained for an instant after the energizing circuit is broken. Relay 103 is a polarized relay, the winding 104 being the polarizing winding. The winding 104 is of German silver wire and does not energize the relay sufficiently to enable it to attract its armature. Coils 106 and 107 are balancing coils whose purpose will be explained later.

Associated with each repeater is a rotary 130

switch S which may be of any suitable construction the only requirements being that it consist of two separate sets of contacts and wipers for each set, such wipers being continuously in contact with at least one of the contacts in their respective sets, and adapted to be rotated by a suitable motor mechanism. As shown diagrammatically in Fig. 2, the two sets of contacts or banks form each an arc of one third of a circle and there are three multiple wipers for each bank spaced at an angle of 120° from each other so that as one of the wipers leaves the last contact of its bank a multiple wiper will ride up on the first contact. The contacts 139 are all connected to ground at G^{31} except the first contact which is the one upon which wiper W' or its multiple wiper normally rests. In the other bank the 1st, 3rd, 5th, etc., contacts are marked 138 and are multiplied together and connected to ground at G^{17} . The alternate contacts are marked 137. A certain number of these alternate contacts 137 are multiplied together and connected through the resistance r' with the positive pole of battery B'. The remaining contacts 137 are multiplied together and connected to ground at G^{17} .

Connection is made for talking purposes with the trunk line L L' by means of the repeating coil R' and at the distant end by means of the repeating coil R². Impulses are transmitted over the two sides of the trunk line in parallel forming what is commonly known as a simplex circuit.

The supervising operator's position P is equipped with listening jacks J, lamps 1, and keys K.

The second selector is of the same general type and construction as the first selector already described. The line relay 140 of the second selector is energized over a circuit closed by the relay 186 which in turn is energized by impulses over the simplex circuit. The relay 193 is a polarized relay similar to the relay 103 of the repeater R.

The connector H is of the same general type and construction as that disclosed in U. S. Letters Patent No. 815,176, granted March 13, 1906 to Keith, Erickson and Erickson, the circuits, however, being modified to enable the switch to operate in a system in which the impulses are delivered over the two sides of the line in series. It has the usual magnets for raising and rotating the shaft and for effecting the release of the same. The private magnet 245 controls the movement of the side switch wipers 252, 253, 254 and 255. The usual back bridge relay 249 feeds talking battery to the called line, and when energized, reverses the incoming lines from the second selector. A ringing relay 251 is also provided which is energized at the proper time in series with the interrupting commutator I' and operates to send

ringing current over the called subscriber's line from the generator 281.

Having given a general description of the apparatus, I will now describe the operation of a system embodying the principles of my invention. It will be explained how a subscriber at A may complete an automatic connection with a subscriber A' in a distant exchange whose toll rate is assumed to be fifteen cents. It will also be explained how the subscriber's meter M will be actuated three times to register such a connection, the actuation of the meter being accomplished automatically in response to an initial impulse from the distant exchange. Further, it will be shown how the calling subscriber can bring about the restoration of the apparatus to normal at the termination of the conversation.

In connection with this description it is to be understood that in multi-office systems such as the one under consideration certain of the selector levels in each exchange contain terminals of trunks leading to the other exchanges. These trunks may terminate either at first selector levels or at second selector levels depending on the size of the exchange to which they lead. In the present case it will be assumed that the trunks leading to the exchange to which A' is connected terminate in first selector levels at the exchange to which A is connected and I have arbitrarily assigned the fifth first selector level to these trunks although any other level would have served equally as well. Then it follows that the first digit of A's telephone number must be 5 since to reach the fifth level the figure five must be called. The remaining digits of A's number are determined by the location of his individual switch in the exchange to which he is connected and will be assumed to be 678. Then his entire number will be 5678.

When the subscriber at A, in making the call, raises the receiver from the hook, a circuit will be completed for the line relay 12 of the line switch C, said circuit extending from ground at G' , through normally closed springs 22 and 21, over line 11 to substation A from whence it returns over line 10, through normally closed springs 20 and 19, winding of line relay 12 to battery. Upon the energization of the line relay a circuit for the pull-in winding 18 of the line switch C is closed as follows: ground at G^2 , armature 24, contact spring 23, pull-in winding 18, to battery at contacts 25 and 26. Upon the energization of the pull-in winding the plunger arm 14 and also the armature 15 are attracted, the former by means of its plunger, causing the springs 27-30 to make connection respectively with the contacts 31-34, and the latter breaking the connection of the springs 19 and 21 with the springs 20 and 22 respectively. The closing of the bank

contacts 27 and 31 and 30 and 34 completes a circuit for the line relay 40 of the selector E as follows: ground at G³, winding 49 of the line relay 40, normally closed contact 5 springs 66 and 65, bank contacts 34 and 30, through the subscriber's loop, bank contacts 27 and 31, normally closed contacts 62 and 63, winding 48 of the line relay 40 to battery. When line relay 40 attracts its armature it 10 closes a circuit for slow acting relay 41 as follows: ground at G⁴, working contacts 56 and 57, winding of relay 41 to battery. Relay 41 in turn closes a circuit for the holding winding 17 of the line switch as follows: 15 ground at G⁷, contact springs 51 and 50, back contacts 32 and 28, holding winding 17 to battery. Although the circuit of the slow acting line relay 12 has already been opened by contacts controlled by the armature 15 it 20 holds its armature 24 attracted long enough to enable the above described holding circuit to take effect and so retain the arm 14 and the armature 15 in operative position.

It will be noticed that a branch of the 25 holding circuit passes through the meter M, but the current flow is not sufficient to operate the meter at this time. A second branch of this circuit extends to the test contacts of the calling line and makes it busy to incoming calls.

Now when the subscriber at A dials the first digit 5, of the number he wants he breaks the continuity of his loop five times which causes the line relay 40 of the first 30 selector E to retract its armature a corresponding number of times. As a result a circuit for the vertical magnet 46 which was prepared and is maintained by the slow acting relay 41, is completed as follows: 35 ground at G⁴, contact springs 56 and 55, normally closed contacts 67 and 68, working contacts 53 and 52, winding of relay 43, winding of vertical magnet 46 to battery. This circuit being closed five times by the 40 retractions of the line relay armature, the vertical magnet operates five times to raise the switch shaft five steps, when the line wipers will be raised to the level assigned to the distant office to which A' is connected. 45 At the first vertical step the off normal contacts 74 and 75 are closed. Contact 75 closes a circuit for the release magnet 42 which for the present is open at contact springs 53 and 54 of relay 41. Contact 74 prepares circuits 50 which will be described. Relay 43 is in series with the vertical magnet and is energized intermittently during the vertical impulses. Since relay 43 is slow acting it retains its armature in an operated position 55 60 during the series of impulses thereby closing a circuit for the private or test relay 45 as follows: ground at G⁶, contact springs 58 and 59, winding of relay 45 to battery. Relay 45 closes a locking circuit for itself as 65 follows: ground at G⁷, contact springs 51

and 50, contact 72, off normal contact 74, contact spring 70 and 69, winding of relay 45 to battery. A branch of this circuit also extends from contact springs 69 to the rotary magnet 47 but remains open for the present at contact springs 59 and 60. A testing circuit is also completed to the private or test wiper 79 by the contacts 69 and 70 and will be described. Now at the end of the series of impulses the relay 43 becomes 75 permanently deenergized and retracts its armature thus closing the circuit already prepared for the rotary magnet as follows: ground at G⁷, contact springs 51 and 50, contact 72, off normal contact 74, contact 80 springs 70 and 69, contact springs 59 and 60, contact 73, winding 47 of rotary magnet to battery. The rotary magnet attracts its armature 76 and rotates the shaft one step so that the wipers 78, 79 and 80 make connection with the first set of contacts of the fifth level. Near the end of its stroke the armature 76 opens the contacts 72 and 73 thereby opening the circuit of the rotary magnet and the locking circuit of the test 90 relay 45. The rotary armature accordingly falls back but the deenergization of the test relay 45 depends on the condition of the test contact upon which the private wiper 79 is now resting. If the trunk with which this 95 test circuit is associated is busy, the test contact will have ground potential upon it and a holding circuit for the test relay 45 will exist as follows: ground on test contact, private wiper 79, contact springs 70 and 69, 100 winding of test relay 45 to battery. Then the test relay will remain energized and as the rotary armature returns to normal position and closes the contacts 72 and 73 the rotary magnet will again be energized and 105 will move the wipers 78, 79 and 80 into connection with the second set of contacts of the fifth level. In this manner the wipers will continue to be rotated until they reach an idle trunk as indicated by the absence of 110 ground on the test contact.

The test relay 45 will then fall back and the wipers 78, 79 and 80 will be brought to rest on the contacts of the trunks selected, represented at 81, 82 and 83. When the test 115 relay 45 deenergizes it closes a circuit for the line switching relay 44 as follows: ground at G⁷, contact springs 51 and 50, contact 72, off normal contact 74, contact springs 70 and 71, winding 44 of line switching relay to battery. On attracting its armature, the line switching relay completes a circuit for the line relay 100 of the repeater R as follows: ground at G¹⁴, winding 109 of line relay 100, winding of repeating coil R¹, 120 bank contact 83, wiper 80, contact springs 64 and 65, bank contact 34, spring 30, subscriber's loop and instrument A, spring 27, bank contact 31, contact springs 62 and 61, wiper 78, bank contact 81, wind- 130

ing of repeating coil R' , winding 108 of line relay 100 to battery. The line relay 100 attracts its armature and closes a circuit for the slow acting relay 101 as follows: 5 ground at G^{13} , contact springs 111 and 112, winding of slow acting relay 101 to battery.

The slow acting relay closes the following holding circuit: ground at G^{17} , multiple contact 138 of the rotary switch S, wiper W, 10 contact springs 117 and 118, bank contact 82, wiper 79, to spring 70 at which point the circuit divides, one branch extending by way of spring 71, and winding 44 of the line switching relay to battery, and the other 15 branch extending by way of off normal contact 74, contact 72, bank contact 32, spring 28, and winding 17 of the line switch to battery. When the line switching relay 44 was energized it opened the circuit of the 20 line relay 40. The line relay then deenergized and opened the circuit of the slow acting relay 41 which, however, held its armature attracted for an instant in order to give the new holding circuit described above 25 time to be completed at the repeater R. The line switching relay also opens the release circuit which is prepared by the falling back of the line relay and the slow acting relay 41.

30 We have now established connection with the repeater R which terminates in a trunk line leading to the distant exchange. The line relay of the repeater is energized in series with the subscriber's loop and in turn 35 closes the energizing circuit of the relay 101 in a manner previously described. The slow acting relay 101, in addition to closing the holding circuit, prepares a circuit for the slow-acting relay 102 and also closes a circuit 40 for the polarized winding 104 of the polarized relay 103 as follows: ground at G^{12} , contact springs 120 and 119, winding 104 to battery. The winding 104 is of high 45 resistance and comparatively few turns and therefore does not magnetize the coil 103 sufficiently to enable it to attract its armature.

I will now describe a circuit which has 50 been completed by the line relay for sending impulses to the distant office: ground at G^{26} , windings 187 and 188 of relay 186 in series, windings W^7 and W^8 of repeating coil R^2 in parallel, lines L and L' in parallel, windings W^3 and W^4 of repeating coil R' in parallel, 55 balancing coil 106, contact springs 114 and 113 to battery. This circuit is in parallel with another circuit as follows: ground at G^{10} , adjustable resistance r , balancing coil 107, contact springs 114 and 113 to battery. 60 The winding 105 of the polarized relay 103 is bridged across the two parallel circuits as follows: One terminal is connected to the junction of balancing coil 106 with the middle point of the repeating coil winding, 65 the other terminal is connected to the junc-

tion of balancing coil 107 with adjustable resistance r .

It is apparent that the combination of the two parallel circuits with the winding 105 properly bridged between them as described 70 and shown in Fig. 2 forms an arrangement similar to the well known Wheatstone bridge; and it will be shown at the proper time how, by destroying the normal balance of the bridge, current is made to flow in the 75 winding 105 in the proper direction to operatively energize it.

When the impulse sending circuit previously described was closed at the line relay 100, the relay 186 at the distant office was 80 energized and by attracting its armature, closed the following circuits: ground at G^{28} , contact springs 190 and 189, polarizing winding 194 of polarized relay 193 to battery; ground at G^{23} , winding 149 of line 85 relay 140 of second selector F, contact springs 166 and 165, winding W^6 of repeating coil R^2 , contact springs 191 and 192, winding 195 of polarized relay 193, winding W^5 of repeating coil R^2 , contact springs 162 90 and 163, winding 148 of line relay 140 to battery. The line relay 140 is energized over the latter circuit and in turn closes a circuit for the slow acting relay 141 in a 95 manner already described in the case of the first selector E. The winding 195 is so connected that when the current flows through it in the direction described, its magnetizing effect will oppose that of the winding 194 and therefore the relay 193 will remain inoperative.

The subscriber at A may now rotate his dial for the second digit of the desired number, thereby breaking the circuit of the line relay 100 of the repeater R six times. The 105 line relay 100 in turn opens the circuit of the relay 186 at the distant office a like number of times, resulting in six interruptions of the circuit of the line relay 140 of the second selector F. The line relay of the second selector controls the circuit of the vertical magnet in the well known manner which operates to raise the shaft of the second selector to the sixth level, when it is 110 automatically rotated until the wipers arrive at an idle trunk line leading to a connector switch H. The circuits and operation of the second selector are similar to those of the first selector already described; consequently, this description need not be 115 repeated. It should be understood, however, that the second selector banks are terminals of trunk lines leading to connectors while the first selector banks are terminals of trunk lines leading to repeaters 120 or to second selectors.

It is well to return here to the repeater R and trace several circuits resulting from the deenergization of line relay 100 during 125 impulses. At each retraction of the arma-

ture a circuit is closed as follows: ground at G¹³, contact springs 111 and 110, contact springs 115 and 116, winding of relay 102 to battery. Slow acting relay 102 is energized 5 and places a shunt around the balancing coil 106 and since the slow acting relay does not immediately retract its armature when de-energized, it maintains this shunt during the series of impulses. The purpose of this 10 shunt is to decrease the resistance and impedance of the impulse circuit. Now when the balancing coil 106 is shunted out it will be evident at once that the balance of the Wheatstone bridge will be destroyed and 15 current will flow in the winding 105 of the relay 103. The path of this current is as follows: ground at G¹⁰, adjustable resistance r , winding 105 of polarized relay 103, contact springs 122 and 121, contact springs 114 20 and 113 to battery. The winding 105 is so connected, however, that current flowing in the direction described above produces a magnetizing effect in opposition to that produced by the winding 104 and, therefore, the 25 polarized relay 103 remains inoperative at this time.

The operation of a connector of the general type shown herein is well known and since it forms no part of my invention only 30 a general description will be given.

The subscriber at A operates his dial for the third digit 7 of his number, and thereby opens the circuit of the line relay 240 of the connector H, seven times. The relay de-energizes a like number of times and energizes the vertical magnet 246 and slow acting relay 243 in series, thereby raising the shaft of the connector until its wipers are opposite the seventh level of bank contacts. At the 40 end of the series of impulses the slow acting relay 243 de-energizes and breaks the circuit of the private magnet allowing the side switch wipers to move to the second position. The subscriber at A may now operate his 45 dial for the fourth and last digit of his number, which is 8, and thereby breaks the circuit of the line relay 240 eight times. In response to the impulses the line relay de-energizes a corresponding number of times 50 and energizes the rotary magnet and slow acting relay 243 in series, rotating the shaft until its wipers rest upon the eighth set of contacts of the seventh level which are the terminals of the line 5678 to which A' is 55 connected. At the end of the series of impulses the slow acting relay 243 and the private magnet 245 de-energize as before, allowing the side switch wipers to move to the third position. (Assuming the called line to 60 be idle.)

In the third position, the private wiper 261 of the connector is grounded at the side switch wiper 255. This ground extends over the private normal to the holding winding 65 270 of the line switch C' and energizes it to

attract the armature 274, thereby disconnecting the line relay winding 272 from the called line. Also the ringing relay 251, in series with battery and ground through the interrupter I, operates intermittently to send 70 ringing current over the called subscriber's line. A back bridge relay 249 is bridged across the called line in series with the battery, in order to feed talking battery to the 75 called subscriber.

When the subscriber at A' takes off his receiver in response to the ringing of his bell, he closes the circuit of the back bridge relay, which attracts its armature and closes the circuit of the ring cut off relay 250. 80

Also by means of spring contacts 275, 276, 277, and 278, 279, 280 the back bridge relay reverses battery connections to the line of the calling subscriber. This reversal of the direction of current flow in the line has an 85 important result which will be described in detail later.

Connection has now been completed between a subscriber at A in one exchange and a subscriber at A' in a distant exchange and 90 conversation can be carried on without further effort on the part of either subscriber. It only remains to be seen how the meter M of the calling subscriber A shall be actuated a number of times corresponding to the toll 95 rate to the distant office assumed in this case to be fifteen cents.

Returning to Fig. 2 it will be remembered that the polarized relay 193 was inoperative because the magnetizing effects of its two 100 windings opposed each other.

Now when the back bridge relay of connector H pulls up it reverses the direction of current flow in the winding 195 of the polarized relay 193.

The two windings of the relay 193 now assist each other and it at once attracts its armature closing the following circuit: ground at G²⁵, contact springs 196 and 197, lamp 1 to battery. The signal lamp 1, with similar lamps associated with other incoming trunks, is mounted in front of a supervising operator whose duty it is to listen in on an incoming trunk in response to the lighting of the associated lamp and ascertain whether 110 or not the call was successful. If the party answering proves to be the party wanted the supervising operator presses her key K, associated with the trunk in question and has nothing further to do with the connection. 115 The key K short circuits the high resistance winding 187 of the relay 186. The winding 188 is of low resistance having only enough turns to enable the core 186 to keep its armature attracted. 120

It has been explained before how the line L L' in series with the two windings of the coil 186 formed one leg of a Wheatstone bridge. When therefore, the winding 187 is short circuited by the key K, the normal 130

- balance of the bridge will be destroyed and current will flow in the winding 105 of the polarized relay 103 over the following path: ground at G^{22} , contact 198, winding 188, 5 windings W^7 and W^8 of repeating coil R^2 in parallel, wires L and L' in parallel, windings W^3 and W^4 of repeating coil R' in parallel, winding 105 of polarized relay 103, balancing coil 107, contact springs 114 and 10 113 to battery. The current flowing in the direction described above produces a magnetizing effect which strengthens the magnetism due to the current in the polarizing winding 104, and the armature is attracted 15 closing the following circuit: ground at G^{11} , contact springs 123 and 124, winding of relay 130 to battery. Relay 130, upon energizing, prepares a locking circuit for itself by spring contacts 135 and 136, and also 20 closes the following circuit for the motor magnet 131 of the switch S: ground at G^{16} , interrupter I, contact springs 133 and 134, winding of motor magnet 131 to battery.
- The motor magnet 131, under the influence of ground impulses from interrupter I 25 alternately attracts and detracts its armature, thereby causing the wipers W and W' to sweep over their respective bank contacts. At the first step the wiper W' comes on to the 30 first grounded contact 139 and completes the locking circuit for relay 130 as follows: ground at G^{21} , contact 139, wiper W' , contact springs 135 and 136, winding of relay 130 to battery. Also at the first step the 35 wiper W leaves the first grounded contact 138 and makes connection with the first contact 137 which is connected to the positive pole of battery B' . In a circuit already described it has been shown how the subscriber A's meter M was connected in parallel with the holding coil 17 of the line switch C, by means of the contact 16. It has also been stated that the current flowing from 40 ground at G^{17} over the holding trunk and through the meter M was not sufficient to energize it. Now when the wiper W arrives at the first contact 137 the holding trunk is disconnected from ground at G^{17} and connected to the positive pole of battery B' thus 45 connecting the two batteries B' and B in series and causing an increased current to flow through the meter over the following path: ground at G^{21} , through battery B' , resistance r' , contact 137, wiper W, contacts 117 and 118, back contact 82, wiper 50 79, off normal contact 74, contact 72, bank contact 32, spring contact 28, winding of meter magnet 35, contact 16, to battery B and ground at G^{30} . This strengthened current is sufficient to operate the meter M and it 55 registers once. As the wipers W and W' continue to sweep over their banks of contacts it will be readily understood that the meter M will be actuated every time the 60 wiper W encounters a contact 137 connected

as described to battery B' . It is only necessary then to connect as many of the contacts 137 to battery B' as there are desired actuations of the meter M. The particular group of repeaters of which R is one would all 70 have three contacts 137 in their respective switches S connected to battery B' . The fourth contact 137 and all remaining contacts would be connected to ground as shown in order not to interrupt the holding trunk 75 circuit. As the wipers continue to rotate the wiper W' will eventually leave the last contact 139 and its multiple wiper will arrive at the first contact 139. The first contact 139 is ungrounded and therefore the 80 locking circuit of the relay 130 will be broken and it will detract its armature thereby breaking the circuit of the motor magnet 131 and the wipers W and W' will be brought to rest in their normal position. 85

It is apparent that a second group of repeaters similar to R and terminating in trunk lines leading to an exchange whose toll rate is twenty five cents, would have five contacts in banks of the corresponding 90 switches S, connected to battery B' . In the same manner another group of repeaters R might have but one contact in their switches S connected to battery B' thus providing for but one actuation of the calling 95 subscriber's meter. In any case when the calling subscriber pulls the first digit of his number he selects a group of repeaters terminating in trunk lines leading to the desired exchange and whose associated 100 switches S have a certain number of contacts 137 connected to battery B' , the number of contacts so connected depending on the toll rate to the desired exchange.

I will now describe how the subscriber at 105 A, having finished his conversation, accomplishes the disconnection and restoration to normal of the apparatus in use.

When the subscriber at A places his receiver upon the hook the circuit of the line 110 relay 100 is broken. On detracting its armature line relay 100 opens the circuit of the slow acting relay 101 which in turn breaks the holding circuit of the line switch C and of the line switching relay 44 of the first selector. 115 Upon the deenergization of the holding winding 17 the plunger arm 14 withdraws the plunger from the bank thereby separating the spring contacts 27, 28, 29, 30 from the bank contacts 31, 32, 33 and 34. Also the 120 line switching relay 44 closes an energizing circuit for the release magnet 42 of the first selector upon deenergizing, the release magnet withdraws the retaining pawls from the shaft allowing it to return to normal when 125 the circuit of the release magnet is again broken at contact 75. When line relay 100 deenergizes it also breaks the circuit of the relay 186 in the distant office. Upon deenergizing the relay 186 breaks the circuit 130

of the line relay 240 of the connector H. The line relay in turn breaks the circuit of the slow-acting relay 241 which, upon deenergizing opens the holding circuit of the relay 144 of the second selector F and also closes the circuit of the release magnet 242 of the connector H. Both second selector and connector are then returned to normal in a manner already described in the case of the first selector.

While I have described one form in which my invention may be practised I do not wish to be strictly held to the form shown herein, but desire rather to include all modifications which may come within the scope of the appended claims.

What I claim as my invention is:

1. In a telephone system, a toll assessing device, means for controlling said device, a Wheatstone bridge, and other means for unbalancing said bridge for controlling said device through the medium of said first means.

2. In a telephone system, a toll assessing device, means for controlling said device, a Wheatstone bridge, other means for unbalancing said bridge for controlling said device through the medium of said first means, said first means including a circuit for said device, a source of potential in said circuit, and a source of potential for boosting the first potential in said circuit to control said device.

3. In a telephone system, a toll assessing device, means for controlling said device, a Wheatstone bridge, other means for unbalancing said bridge for controlling said device through the medium of said first means, said first means including a circuit for said device, a source of potential in said circuit, a source of potential for boosting the first potential in said circuit to control said device, and an impulse sender for controlling the application of said booster potential to said circuit.

4. In a telephone system, a toll assessing device, means for controlling said device, a Wheatstone bridge, other means for unbalancing said bridge for controlling said device through the medium of said first means, said first means including a circuit for said device, a source of potential in said circuit, a source of potential for boosting the first potential in said circuit to control said device, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.

5. In a telephone system, a toll assessing device, means for controlling said device, a

Wheatstone bridge, and manually controlled means for unbalancing said bridge for controlling said device through the medium of said first means.

6. In a telephone system, a toll assessing device, means for controlling said device, a Wheatstone bridge, manually controlled means for unbalancing said bridge for controlling said device through the medium of said first means, said first means including a circuit for said device, a source of potential in said circuit, and a source of potential for boosting the first potential in said circuit to control said device.

7. In a telephone system, a toll assessing device, means for controlling said device, a Wheatstone bridge, manually controlled means for unbalancing said bridge for controlling said device through the medium of said first means, said first means including a circuit for said device, a source of potential in said circuit, a source of potential for boosting the first potential in said circuit to control said device, and an impulse sender for controlling the application of said booster potential to said circuit.

8. In a telephone system, a toll assessing device, means for controlling said device, a Wheatstone bridge, manually controlled means for unbalancing said bridge for controlling said device through the medium of said first means, said first means including a circuit for said device, a source of potential in said circuit, a source of potential for boosting the first potential in said circuit to control said device, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.

9. In a telephone system, a line, a toll assessing device associated with said line, means for controlling said device, another line, means for connecting said two lines, a subscriber's telephone station for the second line, a Wheatstone bridge, and means for unbalancing said bridge for controlling said device through the medium of said first means, said first means including a circuit for said device controlled by said second means.

10. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a source of

potential in said circuit, and a source of potential for boosting said first potential in said circuit to control said device.

11. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a source of potential in said circuit, a source of potential for boosting said first potential in said circuit to control said device, and an impulse sender for controlling the application of said booster potential to said circuit.
12. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.

13. In a telephone system, a line, a toll assessing device associated with said line, means for controlling said device, another line, means for connecting said two lines, a subscriber's telephone station for the second line, a Wheatstone bridge, and manually controlled means for unbalancing said bridge for controlling said device through the medium of said first means, said first means including a circuit for said device controlled by said second means.

14. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a source of potential in said circuit, and a source of potential for boosting said first potential in said circuit to control said device.

15. In a telephone system, a line, a toll assessing device associated with said line, means for controlling said device, another line, means for connecting said two lines, a

subscriber's telephone station for the second line, a Wheatstone bridge, manually controlled means for unbalancing said bridge for controlling said device through the medium of said first means, said first means including a circuit for said device controlled by said second means, a source of potential in said circuit, a source of potential for boosting said first potential in said circuit to control said device, and an impulse sender for controlling the application of said booster potential to said circuit.

16. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.

17. In a telephone system, a line, a toll assessing device associated with said line means for operating said device, another line, means for connecting the two lines, a subscriber's telephone station for said second line, a signal for said telephone controlled by the subscriber on said first line, an operator, a signal for said operator controlled by said second subscriber when answering said signal, a Wheatstone bridge, and means controlled by said operator for unbalancing said bridge for operating said device through the medium of said first means when the second subscriber signals said operator.

18. In a telephone system, a line, a toll assessing device associated with said line, means for operating said device, another line, means for connecting the two lines, a subscriber's telephone station for said second line, a signal for said telephone controlled by the subscriber on said first line, an operator, a signal for said operator controlled by said second subscriber when answering said first signal, a Wheatstone bridge, means controlled by said operator for unbalancing said bridge for operating said device through the medium of said first means when the second subscriber signals said operator, said first means including a circuit for said device, a source of potential in said circuit, and a source of potential for boosting the first potential in said circuit to control said device.

- means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, said second means including a leg of said bridge, said second means including also a progressively movable switch between said bridge and the called line, and means for sending impulses over said leg for operating said switch.
34. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a source of potential in said circuit, a source of potential for boosting said first potential in said circuit to control said device, said second means including a leg of said bridge, said second means including also a progressively movable switch between said bridge and the called line, and means for sending impulses over said leg for operating said switch.
35. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a source of potential in said circuit, a source of potential for boosting said first potential in said circuit to control said device, an impulse sender for controlling the application of said booster potential to said circuit, said second means including a leg of said bridge, said second means including also a progressively movable switch between said bridge and the called line, and means for sending impulses over said leg for operating said switch.
36. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a line associated with said device, a trunk line,
- an automatic switch for connecting said line and trunk, a busy test circuit for said trunk, another line and another switch having access to said trunk, said trunk and said bridge using conductors in common, the circuit for said device and the busy test circuit having a conductor in common, said second means including a leg of said bridge, said second means including also a progressively movable switch between said bridge and the called line, and means for sending impulses over said leg for operating said switch.
37. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, said second means including, a leg of said bridge, said second means including also a progressively movable switch between said bridge and the called line, and means for sending impulses over said leg for operating said switch.
38. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a source of potential in said circuit, a source of potential for boosting said first potential in said circuit to control said device, said second means including a leg of said bridge, said second means including also a progressively movable switch between said bridge and the called line, and means for sending impulses over said leg for operating said switch.
39. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a source of potential in said circuit, a source of potential for boosting said first potential in said circuit to control said device, an impulse sender for controlling the application of said booster potential to said circuit, said second means including a leg of said bridge, said second means including also a progressively movable switch between said bridge and the called line, and means for sending impulses over said leg for operating said switch.

able switch between said bridge and the called line, and means for sending impulses over said leg for operating said switch.

40. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common, said second means including a leg of said bridge, said second means including also a progressively movable switch between said bridge and the called line, and means for sending impulses over said leg for operating said switch.

41. In a telephone system, a line, a toll assessing device associated with said line, means for controlling said device, another line, means for connecting said two lines, a subscriber's telephone station for the second line, a Wheatstone bridge, and means for unbalancing said bridge for controlling said device through the medium of said first means, said first means including a circuit for said device controlled by said second means, said second means including a leg of said bridge, said means including also a progressively movable switch between the first line and said bridge, said bridge provided with means for placing said device under the control of said bridge.

42. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a source of potential in said circuit, and a source of potential for boosting said first potential in said circuit to control said device, said second means including a leg of said bridge, said means including also a progressively movable switch between the first line and said bridge, said bridge provided with means for placing said device under the control of said bridge.

43. In a telephone system, a line, a toll assessing device associated with said line, means for controlling said device, another line, means for connecting said two lines, a subscriber's telephone station for the second line, a Wheatstone bridge, manually controlled means for connecting said two lines, a subscriber's telephone station for the second line, a Wheatstone bridge, means for unbalancing said bridge for controlling said device through the medium of said first means, said first means including a circuit for said device controlled by said second means, a source of potential in said circuit, and a source of potential for boosting said first potential in said circuit to control said device, said second means including a leg of said bridge, said means including also a progressively movable switch between the first line and said bridge, said bridge provided with means for placing said device under the control of said bridge.

44. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a source of potential in said circuit, and a source of potential for boosting said first potential in said circuit to control said device, and an impulse sender for controlling the application of said booster potential to said circuit, said second means including a leg of said bridge, said means including also a progressively movable switch between the first line and said bridge, said bridge provided with means for placing said device under the control of said bridge.

45. In a telephone system, a line, a toll assessing device associated with said line, means for controlling said device, another line, means for connecting said two lines, a subscriber's telephone station for the second line, a Wheatstone bridge, and manually controlled means for unbalancing said bridge for controlling said device through the medium of said first means, said first means including a circuit for said device controlled by said second means, said second means including a leg of said bridge, said means including also a progressively movable switch between the first line and said bridge, said bridge also provided with means for placing said device under the control of said bridge.

46. In a telephone system, a line, a toll assessing device associated with said line, means for controlling said device, another line, means for connecting said two lines, a subscriber's telephone station for the second line, a Wheatstone bridge, manually controlled means for connecting said two lines, a subscriber's telephone station for the second line, a Wheatstone bridge, means for unbalancing said bridge for controlling said device through the medium of said first means, said first means including a circuit for said device controlled by said second means, a source of potential in said circuit, and a source of potential for boosting said first potential in said circuit to control said device, said second means including a leg of said bridge, said means including also a progressively movable switch between the first line and said bridge, said bridge provided with means for placing said device under the control of said bridge.

trolled means for unbalancing said bridge for controlling said device through the medium of said first means, said first means including a circuit for said device controlled by said second means, a source of potential in said circuit, and a source of potential for boosting said first potential in said circuit to control said device, said second means including a leg of said bridge, said means including also a progressively movable switch between the first line and said bridge, said bridge provided with means for placing said device under the control of said bridge.

47. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a source of potential in said circuit, a source of potential for boosting said first potential in said circuit to control said device, and an impulse sender for controlling the application of said booster potential to said circuit, said second means including a leg of said bridge, said means including also a progressively movable switch between the first line and said bridge, said bridge provided with means for placing said device under the control of said bridge.

48. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means including a circuit for said device controlled by said second means, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common, said second means including a leg of said bridge, said means including also a progressively movable switch between the first line and said bridge, said bridge provided with means for placing said device under the control of said bridge.

49. In a telephone system, a toll assessing device associated with a line, means for controlling said device, a plurality of Wheatstone bridges, and means for unbal-

ancing any one of said bridges for controlling said device through the medium of said first means.

50. In a telephone system, a toll assessing device associated with a line, means for controlling said device, a plurality of Wheatstone bridges, means for unbalancing any one of said bridges for controlling said device through the medium of said first means, and a progressively movable switch controlled over said line for placing said device under the control of one of said bridges.

51. In a telephone system, a toll assessing device associated with a line, means for controlling said device, a plurality of Wheatstone bridges, means for unbalancing any one of said bridges for controlling said device through the medium of said first means, a progressively movable switch controlled over said line for placing said device under the control of one of said bridges, and means associated with each bridge for controlling said device to assess a different toll.

52. In a telephone system, a toll assessing device associated with a line, means for operating said device, Wheatstone bridges divided into groups, means for unbalancing any one of said bridges for controlling said device through the medium of said first means, and a progressively movable switch controlled over said line for electing any one of said groups of bridges for placing said device under the control of any one of the bridges in the elected group.

53. In a telephone system, a toll assessing device associated with a line, means for operating said device, Wheatstone bridges divided into groups, means for unbalancing any one of said bridges for controlling said device through the medium of said first means, a progressively movable switch controlled over said line for electing any one of said groups of bridges for placing said device under the control of any one of the bridges in the elected group, and means associated with each bridge in the elected group for controlling said device to assess the same toll.

54. In a telephone system, a toll assessing device associated with a line, means for operating said device, Wheatstone bridges divided into groups, means for unbalancing any one of said bridges for controlling said device through the medium of said first means, a progressively movable switch controlled over said line for electing any one of said groups of bridges for placing said device under the control of any one of the bridges in the elected group, means associated with each bridge in the elected group for controlling said device to assess the same toll.

55. In a telephone system, a toll device associated with a line, an operating circuit for said device, a plurality of automatic circuit controllers associated with said device, each having a progressively movable element and each controlling the device to assess a different toll, said operating circuit closed through said element.
56. In a telephone system, a toll device associated with a line, an operating circuit for said device, a plurality of automatic circuit controllers associated with said device, each having a progressively movable element and each controlling the device to 65 assess a different toll, said operating circuit closed through said element, a called line, means for connecting the two lines, a balance circuit associated with each one of said controllers, a signal associated with the 70 called line, means for operating said signal from said called line, and means for unbalancing one of said circuits after said signal is operated for operating said toll device.
57. In a telephone system, a toll device associated with a line, an operating circuit for said device, a plurality of automatic circuit controllers associated with said device, each having a progressively movable element and each provided with means for operating said device a number of times each 75 time the controller is brought into operation to assess a toll, a called line, means for connecting the two lines, a balance circuit associated with each one of said controllers, a signal associated with the called line, means for operating said signal from said called line, and means for unbalancing one of said circuits after said signal is operated for operating said toll device.
58. In a telephone system, a toll device associated with a line, an operating circuit for said device, a plurality of automatic circuit controllers associated with said device, each having a progressively movable element and each provided with means for operating said device a number of times each 80 time the controller is brought into operation to assess a toll, an automatic switch for automatically connecting said line with any 85 one of said circuit controllers, a called line, means for connecting the two lines, a balance circuit associated with each one of said controllers, a signal associated with the called line, means for operating said signal from said called line, and means for unbalancing one of said circuits after said signal is operated for operating said toll device.
59. In a telephone system, a toll assessing 90 device associated with a line, an operating circuit for said device, an automatic circuit controller associated with said device, said controller having a progressively movable element and provided with means for operating said device a number of times each 95 time the controller is brought into operation to assess a toll, said operating circuit closed through said element, another line, means for connecting the two lines, a signal under the control of said second line, a balance 100 circuit associated with said controller, and means for unbalancing said circuit after the said signal is operated to bring said controller into operation.
60. In a telephone system, a toll assessing device associated with a line, an operating circuit for said line, means for extending a connection to any one of a plurality of lines, automatically controlled equipment having a progressively movable element associated 105 with said device, and means for starting said equipment after connection is extended to the called line for variably operating said device depending upon the line to which connection is extended, said operating circuit closed through said progressively movable element.
61. In a telephone system, a measured service device associated with a line, an operating circuit for said device, means for extending a connection from said line to any one of a group of lines, automatic circuit controlling equipment having a progressively movable element associated with 110 said group of lines for controlling the operation of said device, said equipment arranged for variably operating said measured service device whereby the device is operated to assess one toll if the first line is connected to one line of the group, and operated to assess a different toll if the line is connected to another line of the group, said operating circuit closed through said element.
62. In a telephone system, a toll assessing device, means for controlling said device, a Wheatstone bridge, other means for unbalancing said bridge for controlling said device through the medium of said first means, said first means including a circuit for said device, a source of potential in said circuit, a source of potential for boosting the first potential in said circuit to control said device, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common, said conductor being one of the conductors of said trunk.
63. In a telephone system, a toll assessing device, means for controlling said device, a Wheatstone bridge, other means for unbalancing said bridge for controlling said device through the medium of said first means, said first means including a circuit for said 120 conductor being one of the conductors of said trunk.

- device, a source of potential in said circuit, a source of potential for boosting the first potential in said circuit to control said device, an impulse sender for controlling the application of said booster potential to said circuit, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.
64. In a telephone system, a toll assessing device, means for controlling said device, a Wheatstone bridge, other means for unbalancing said bridge for controlling said device through the medium of said first means, said first means including a circuit for said device, a source of potential in said circuit, a source of potential for boosting the first potential in said circuit to control said device, an impulse sender for controlling the application of said booster potential to said circuit, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common, said conductor being one of the conductors of said trunk.
65. In a telephone system, a toll assessing device, means for controlling said device, a Wheatstone bridge, manually controlled means for unbalancing said bridge for controlling said device through the medium of said first means, said first means including a circuit for said device, a source of potential in said circuit, a source of potential for boosting the first potential in said circuit to control said device, an impulse sender for controlling the application of said booster potential to said circuit, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.
66. In a telephone system, a toll assessing device, means for controlling said device, a Wheatstone bridge, manually controlled means for unbalancing said bridge for controlling said device through the medium of said first means, said first means including a circuit for said device, a source of potential in said circuit, a source of potential for boosting the first potential in said circuit to control said device, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.
67. In a telephone system, a toll assessing device, means for controlling said device, a Wheatstone bridge, manually controlled means for unbalancing said bridge for controlling said device through the medium of said first means, said first means including a circuit for said device, a source of potential in said circuit, a source of potential for boosting the first potential in said circuit to control said device, an impulse sender for controlling the application of said booster potential to said circuit, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.
68. In a telephone system, a toll assessing device, means for controlling said device, a Wheatstone bridge, manually controlled means for unbalancing said bridge for controlling said device through the medium of said first means, said first means including a circuit for said device, a source of potential in said circuit, a source of potential for boosting the first potential in said circuit to control said device, an impulse sender for controlling the application of said booster potential to said circuit, a line associated with said device, a trunk line, an automatic switch for connecting said line and trunk, a busy test circuit for said trunk, another line and another switch having access to said trunk, said trunk and said bridge using conductors in common, the circuit for said device and the busy test circuit having a conductor in common.
69. In a telephone system, a line, a toll assessing device associated with said line, means for controlling said device, another line, means for connecting said two lines, a subscriber's telephone station for the second line, a Wheatstone bridge, means for unbalancing said bridge for controlling said device through the medium of said first means, said first means including a circuit for said device controlled by said second means, a line associated with said device, a trunk line, an automatic switch for connecting said line and trunk, a busy test circuit for said trunk, another line and another switch having access to said trunk, said

- trunk and said bridge using conductors in common, the circuit for said device and the busy test circuit having a conductor in common, said trunk and said device using conductors in common. 77. In a telephone system, a plurality of 65 lines, a toll assessing device for each line, a Wheatstone bridge common to said lines, an automatic progressively movable switch for connecting any one of said lines with said bridge, and means for unbalancing said bridge to operate said device. 70
70. In a telephone system, a line, a toll assessing device associated with said line, means for controlling said device, another line, means for connecting said two lines, a subscriber's telephone station for the second line, a Wheatstone bridge, manually controlled means for unbalancing said bridge for controlling said device through the medium of said first means, said first means 10 including a circuit for said device controlled by said second means, a line associated with said device, a trunk line, an automatic switch for connecting said line and trunk, a busy test circuit for said 15 trunk, another line and another switch having access to said trunk, said trunk and said bridge using conductors in common, the circuit for said device and the busy test circuit having a conductor in common, said trunk 20 and said device using conductors in common. 78. In a telephone system, a line, a toll assessing device for said line, a trunk line, an automatic switch for extending a connection from said line, and an operating circuit 75 for said switch and for said device including the two sides of said trunk line in parallel. 79. In a telephone system, a line, a toll assessing device for said line, a trunk line, 80 an automatic switch for extending a connection from said line, an operating circuit for said switch including the two sides of said trunk line in parallel, and means controlled over said operating circuit for causing said device to register a predetermined 85 number of times. 80. In a telephone system, a line, a toll assessing device for said line, a trunk line, an automatic switch for extending a connection from said line, an operating circuit for said switch including the two sides of said trunk line in parallel, and automatic means controlled over said operating circuit for causing said device to register a variable 90 number of times. 81. In a telephone system, a line, a meter for said line, a trunk line, an automatic switch for extending a connection from said line, a simplex circuit superimposed on 95 said trunk line, means for operating said switch over said simplex circuit, a Wheatstone bridge for controlling the operation of said meter, one arm of said bridge including said simplex circuit. 100 105
71. In a telephone system, a meter, a circuit for operating said meter, a circuit closer for controlling said circuit, a Wheatstone bridge, and means for unbalancing said bridge to operate said circuit closer. 82. In a telephone system, a line, a meter for said line, a trunk line, an operator's position, means for extending a connection from said line over said trunk line to said operator's position, a simplex circuit including the two sides of said trunk line in parallel, and automatic means controlled by the operator over said simplex circuit for operating said meter to register a call. 110
72. In a telephone system, a measured service device, a circuit for operating said device, a progressively movable circuit closer for controlling said circuit, a Wheatstone bridge, and means for unbalancing said bridge to operate said circuit closer. 83. In a telephone system, a line, a meter 115 for said line, a trunk line, an operator's position, means for extending a connection from said line over said trunk line to said operator's position, a simplex circuit including the two sides of said trunk line in parallel, and automatic means controlled by the operator over said simplex circuit for operating said meter a predetermined number of times to register a call. 120
73. In a telephone system, a line, a toll device individual to said line, means for controlling said device, a trunk line, a Wheatstone bridge individual to said trunk, means for connecting said line and trunk, and means for unbalancing said bridge to operate said device through the medium of said first means. 84. In a telephone system, a line, a meter 125 for said line, a trunk line, an operator's position, means for extending a connection from said line over said trunk line to said
74. In a telephone system, a plurality of lines, a toll assessing device for each line, a Wheatstone bridge common to said lines, means for connecting any one of said lines with said bridge, and means for unbalancing said bridge to operate said device. 55
75. In a telephone system, a plurality of lines, a toll assessing device for each line, a Wheatstone bridge common to said lines, an automatic switch for connecting any one of said lines with said bridge, and means for unbalancing said bridge to operate said device. 60
76. In a telephone system, a plurality of lines, a toll assessing device for each line, a Wheatstone bridge common to said lines, means for connecting any one of said lines with said bridge, and manually controlled means for unbalancing said bridge to operate said device. 65

operator's position, a simplex circuit including the two sides of said trunk line in parallel, and automatic means controlled by the operator over said simplex circuit for operating said meter to assess a single or a double toll charge for different calls for the same length of time.

85. In a telephone system, a line, a meter for said line, a trunk line, an operator's position, means for extending a connection from said line over said trunk line to said operator's position, a simplex circuit including the two sides of said trunk line in parallel, and automatic means controlled by the operator over said simplex circuit for operating said meter to assess a double toll charge for a call regardless of the length of time.

86. In a telephone system, a line, a meter for said line, a trunk line, an operator's position, means for extending a connection from said line over said trunk line to said operator's position, a simplex circuit including

the two sides of said trunk line in parallel, and automatic means controlled by the operator over said simplex circuit for operating said meter a predetermined number of times when the initial charge is made. 25

87. In a telephone system, a line, a meter for said line, a trunk line, an operator's position, means for extending a connection from said line over said trunk line to said operator's position, a simplex circuit including the two sides of said trunk line in parallel, and automatic means controlled by the operator over said circuit for operating said meter to register a toll charge when the initial charge is made. 30 35

Signed by me at Chicago, Cook county, Illinois, this 9th day of July, 1915.

WINFRED T. POWELL.
